James Stewart Whitaker.

UNITED STATES PATENT OFFICE.

FRANK MATHEWS, OF CROYDON, AND STANLEY DRUMMOND BLACK, OF LONDON, ENGLAND.

REGISTERING TICKET PUNCH.

Application filed October 14, 1921. Serial No. 507,695.

To all whom it may concern:

Be it known that we, FRANK MATHEWS and STANLEY DRUMMOND BLACK, subjects of the King of Great Britain, residing, respectively, at 50 Compton Road, Croydon, Surrey, England, and 56 Tabernacle Street, London, England, have invented new and useful Improvements in Registering Ticket Punches, of which the following is a specification.

This invention relates to registering ticket punches used by conductors on street passenger vehicles for checking the issue of tickets, of the kind in which a bell is sounded and in which the complete reciprocations of the ticket punch are controlled through the medium of a double rack and a double armed rocking pawl engaging therewith, the object of the invention being to improve and simplify the construction, and to render the instrument more reliable and less subject to breakdown through wear of working parts than heretofore.

According to our invention the main operating spring which also functions for operating the gong hammer is located within a slot in the main slide which is in the form of a link pivoted to the head slide and directly or indirectly to the operating lever.

In a suitable arrangement for carrying out the invention the main slide is slotted longitudinally and the main spring is arranged within this slot, one end of the spring bearing against one end of the slot whilst the other end of the spring bears against one side of a plunger or block slidable within the slot and the opposite side of which block is flat and bears against a flat face on the boss of the gong hammer. This boss passes through the slot in the main slide and is pivoted to the base of the ticket punch. To the main slide is pivoted the double-armed rocking pawl, whilst the double rack for engagement therewith is pivoted to the base of the punch and connected to the said pawl by a spiral spring, the said double rack being capable of a rocking movement on its pivot and which motion is limited by a pin engaging a slot. The gong hammer is actuated by a projection on the double armed rocking pawl engaging and riding past a projection on the said hammer.

In the accompanying drawing—

Figure 1 is a front elevation of part of a

registering ticket punch illustrating the improvements. 55

Figure 2 is an elevation at right angles to Figure 1.

Figure 3 is a horizontal section on the line 3—3, Figure 1, and 60

Figure 4 is a similar view to Figure 1 showing another position of the parts.

a is the base or main plate upon which all the mechanism of the punch is mounted, *b* the head in which slides the punch proper *c* 65 carried upon the head-slide *d*. *e* is the operating lever for the punch, which lever carries the thumb-piece *f* and *g* is the bell or gong indicated by the dotted lines. All the foregoing parts are of usual construction. 70

We will now describe the improvements.

h is the main-slide which is in the form of a link connecting the head-slide *d* with the operating lever *e* by means of the pivot pins *i*. As clearly indicated in Figure 1, the link 75 *h* and lever *e* are so relatively positioned as to impart a minimum lateral movement to the said link during the reciprocations of the punch *c*. The main slide *h* is provided longitudinally with a slot *j*, a pin *k* secured 80 to the base-plate *a* projecting through the lower end of the said slot and having pivoted thereon the hammer *l* for striking the gong *g*. In the upper part of the slot *j* is arranged the main actuating spring *m* of spiral 85 form, one end of which bears against the upper end of the said slot, preferably through the medium of a plate *n* having a downwardly extending pin *o* to receive the spring. The other or lower end of the spring 90 bears against a plunger or block *p* the lower face *q* of which is flat and the upper part of which consists of a pin which extends into a longitudinal recess in the pin *o*, and telescopes within the pin *o*. The face *q* of the 95 plunger bears against a flat face *r* on the boss of the hammer *l* and holds it in the position indicated clearly in Figure 1 by the pressure of the spring *m*.

s is the double pawl pivoted on a pin *t* 100 fixed to the main slide *h* and *u* is the double rack pivoted at *u*¹ to the base-plate *a*. This rack is provided with a set of ratchet teeth *u*² on the upper end and a series of teeth *u*³ in the form of steps on the lower end, with 105 which two sets of teeth the toothed ends *t*¹, *t*² of the pawl are designed to co-act, respectively, in the known manner, to compel

the full operations of the lever *e* in opposite directions, the tooth *t*¹ of the pawl *s* being held in engagement with the rack teeth *u*² during the downward movement of the main slide *h* by a relatively weak spring *t*³ attached at one end to the rack *u*. The pawl has a nose or projection *t*⁴ which presses back the hammer *l* by contact with a projection *l*¹ thereon, during such downward movement, and releases it to strike the gong *g* by riding over the said projection *l*¹ just before reaching the limit of such movement. Figure 4 indicates the position of the parts when reaching the limit of the said downward movement. On the upward movement of the parts, the tooth *t*¹ of the pawl *s* will be moved clear of the ratchet teeth *u*² as the projection *t*⁴ on the said pawl rides over the projection *l*¹ on the hammer, which it clears just before the limit of the upward movement of the main slide *h*. This movement of the pawl will move the end *t*² thereof into engagement with the steps *u*³ on the rack, the rack yielding against the pull of the spring *t*³ as the said end *t*² rides over the steps or teeth *u*³, such yielding movement being determined by a recess or slot *v* in the rack and a stop pin *w*, on the base *a*, projecting within the said recess. *x* is a projection on the main slide *h* designed to operate numerating mechanism (not shown) in the known manner.

The parts are shown in Figs. 1 and 2 in their normal positions, and in Fig. 4 they are shown in the positions to which they are moved by the operator in the use of the punch. It will be understood from the foregoing description that the punch, *c*, is carried by the head slide, *d*, and is brought down through the material to be punched by the operation of the device, as indicated in Fig. 4. The operator places his thumb upon the thumb piece, *f*, see Figs. 1 and 2, and presses downwardly, thereby drawing down the slotted operating lever *e* and the main slide, *h*, together with the head slide and punch, *c*. As the stud, *k*, on which the bell hammer is mounted is fixed to the casing, the spring, *m*, will be compressed by the downward movement of the main slide, *h*. The downward movement of the slide, *h*, carries with it the double ended pawl, the upper end, *t*¹ of which is held in engagement with the teeth, *u*², on the double rack by the light spring, *t*³. The pawl *t*¹ slides over the teeth, *u*², on the downward movement, which insures the full downward movement of the slide, and on the downward stroke, the projection, *t*⁴, engages the projection *l*¹, on the hammer, *l*, pushing it away from the gong and passing over the projection *l*¹. This rocks the hammer, *l*, on its stationary stud, *k*, and moves the plunger or block, *p*, slightly upwardly on account of the engagement between the lower face, *q*, of the plunger, *p*,

and the flat face on the hammer *o* which it engages. As soon as the projection, *t*⁴, on the pawl passes the hammer lug, *l*¹, the hammer is thrown toward the bell by the action of the spring, *m*, and plunger block, *p*, the over-movement of the hammer ringing the bell and the engagement of the face, *q*, of the plunger with the flat face of the hammer, restoring the hammer to its normal position after the stroke, with the hammer sufficiently removed from the bell, as shown in Fig. 1, to allow it to sound, as is usual in bell hammer constructions. As soon as the punch has been operated fully by the downward movement of the lever, *e*, the operator releases the thumb piece, *f*, and the spring, *m*, restores the lever, *e*, slide, *h*, head slide, *d*, and punch, *c*, to normal position. On the upward movement of the slide, *h*, the projection, *t*⁴, is caused to engage the hammer lug, *l*¹, as shown in Fig. 4, but this time the lower end of the pawl moves to the right, carrying with it the double rack, passing over the hammer lug, *l*¹, without operating the hammer, and as it passes over the lug, *l*¹, the lower end, *t*², of the double pawl engages the steps or teeth, *u*³, in the lower end of the double rack, thus insuring that the parts shall be returned fully to normal position before another downward movement of the lever, *e*, and main slide, *h*, can be effected. The light spring *t*³, acts to insure the proper coaction of the double pawl and double rack. In the normal position of the apparatus, as shown in Fig. 1, it draws the upper end, *t*¹, of the double pawl into engagement with the teeth, *u*², and when the lever, *e*, is depressed, as shown in Fig. 4, in which position of the apparatus the pawl has been carried downwardly with respect to the rack, the spring draws the lower end of the double rack and the lower end, *t*², of the pawl, together.

Claims:

1. In a registering ticket punch of the kind hereinbefore referred to, the combination with the operating lever and the head slide carrying the punch proper of a slotted link pivoted to the said lever and slide, a block or abutment within the slot and held against movement in one direction longitudinally of the said slot and a spring arranged between the said abutment and one end of the slot to return the operating lever and punch after punching a ticket. 110

2. In a registering ticket punch of the kind hereinbefore referred to, the combination with the operating lever and the head slide carrying the punch proper of a slotted link pivoted to the said lever and slide, a block or abutment within the slot and held against movement in one direction longitudinally of the said slot and a spring arranged between the said abutment and one end of the slot to return the operating lever 125

- and punch after punching a ticket, a double armed rocking pawl pivoted to the said link and a double rack co-acting with the said pawl and pivoted to the casing of the ticket 5 punch to effect the complete reciprocations of the punch proper.
3. In a registering ticket punch of the kind hereinbefore referred to, the combination with the operating lever and the head 10 slide carrying the punch proper of a slotted link pivoted to the said lever and slide, a block or abutment within the slot and held 15 against movement in one direction longitudinally of the said slot and a spring arranged ranged between the said abutment and one 20 end of the slot to return the operating lever and punch after punching a ticket, the said abutment being free to move longitudinally in the said slot against the tension of said 25 spring, and being provided with a flat exterior face on the side opposite the spring and a gong hammer pivoted to the punch casing, and provided with a flat face cooperating with the flat face of said abutment under the pressure of the spring in said slot.
4. In a registering ticket punch of the
- kind hereinbefore referred to, the combination with the operating lever and the head slide carrying the punch proper of a slotted link pivoted to the said lever and slide, a block or abutment within the slot and held 30 against movement in one direction longitudinally of the said slot and a spring arranged between the said abutment and one end of the slot to return the operating lever and punch after punching a ticket, the said abutment being free to move longitudinally in the said slot against the tension of said 35 spring, and being provided with a flat exterior face on the side opposite the spring and a gong hammer pivoted to the punch casing, and provided with a flat face co-operating with the flat face of said abutment under the pressure of the spring in said slot, 40 a double arm pawl, a double rack for the same, and co-acting projections on the hammer and the double arm pawl to effect the operation of the hammer and the engagement of the pawl with the double rack. 45
